PIPE STABBING DEVICE

Floyd L. Scott, Houston, Tex., assignor to Hughes
Tool Company, Houston, Tex., a corporation of
Delaware

Application October 24, 1946, Serial No. 705,421

4 Claims. (Cl. 255—1)

1

This invention relates to a pipe stabbing device and more particularly to a device of novel construction for facilitating the making-up of tool joints or pipe connections where the two sections to be interconnected are disposed in a vertical position.

When drilling wells by the rotary method the drill bit is lowered into the well bore on a drill string comprising a plurality of drill stem sections threadedly interconnected in a vertical position. As the bit is lowered, either when going into the hole or when a new section of drill string is added during drilling, each succeeding section is brought into vertical alignment with the next preceding section projecting from the top of the well bore.

A section of pipe or drill string to be added should be quickly and accurately brought into vertical position above the string to which it is to be attached. However, when such sections, which are frequently thrubbles and fourbles, 90 feet and 120 feet in length, respectively, are hoisted from their upper ends by the traveling block in the derrick, difficulty is experienced in controlling movement of the lower ends of these sections to bring them accurately into position for proper entry of the pin into the box and final make-up without damage to the mating surfaces.

Elimination of this difficulty is of extreme importance inasmuch as damage to any portion of the pin or box may give rise to leakage either actual or incipient. A similar situation to that just described exists when installing a string of casing within a well and the invention is likewise concerned with facilitating the making-up of connections in casing being lowered into a well bore.

An object of the invention is to provide means for assuring the making up of threaded connections without damage to any portion of the threaded members being interconnected.

Another object of the invention is to accomplish the indicated results with a minimum consumption of time.

A further object is to minimize the amount of labor involved and the hazards incident thereto when making up a tubular string being lowered in the well bore.

A still further object of the invention is to provide a pipe stabbing device of relatively small dimensions and weight which may therefore be easily handled by the operator.

The invention also contemplates the provision of a pipe stabbing device that is so constructed and arranged that it will not interfere with the equipment used for tightening the threaded con-

2

nection once the tubular pipe sections are brought into aligned position.

Still another object of the invention is to provide a device of this type of which the accuracy in aligning of the members being inter-connected is unaffected by external wear upon such members proximate their ends.

The foregoing objects together with other objects and advantages of the invention will be more fully apparent from the following description considered in connection with the accompanying drawings in which:

Fig. 1 is a perspective view of a pipe stabbing device comprising an embodiment of the invention, pipe sections being shown in dotted outline to show the position of the device relative thereto when in use;

Fig. 2 is a plan view of the device;

Fig. 3 is a vertical sectional view taken on the line 3—3 of Fig. 2;

Fig. 4 is a detail showing a modified form of the aligning and stabilizing lugs.

The embodiment of the invention as shown in the drawing comprises a stop member 1 which may be of any desired configuration but the body portion thereof preferably has a flared arcuate interior surface 2 to serve as an abutment for the pin member 3 on the pipe or drill stem section 4 so that such member is stopped in its swinging movement at a point above the complementary box member 5 on the pipe or drill stem section 6 at the upper end of the tubular string being lowered into a well bore.

The stop member 1 is of sufficient vertical extent to assure engagement by the pin member 3 when the section 4 is lifted sufficiently to assure clearance with the box member 5 when the section is swung toward a position of alignment above the box member. Preferably also the stop member 1 is flared at 10 at its upper end while the

lower portion of the member is provided with an inwardly inclined skirt 11. It should be noted that the flare of the stop member 1 is such that the periphery of the pin member 3, rather than

the downwardly extending pin thereon, will engage the interior surface 2 of the member. Furthermore, the skirt 11 has such inclination with the vertical that the pin will not engage this skirt which effects accurate terminal guidance of the pin into the box 5.

The forward edges 12 of the stop member are flared upwardly and outwardly whereby the stop is of such width at its upper end that little difficulty is experienced in guiding the section 4 to the interior of the stop member. Preferably,

though not necessarily, desired flaring is accomplished by having the upper portion of the stop member generated on an arc (Fig. 2) of greater radius than the generating radius at the lower end of the member. The configuration thus provided is flared as above indicated and also provides a rearward wall portion 9 which is substantially vertical and which further assists in accurately guiding the section 4 into make-up position.

A lip 13 forms a substantially vertical continuation of the skirt 11 and the lower edge of this lip tapers forwardly and upwardly at 14, as best seen in Fig. 3. It is intended that the periphery of this lip shall have such radius of curvature that it will fit closely within the counterbore at the upper end of the box member 5 and in this manner the interior surface of the box member serves as the aligning surface for the skirt, and consequently for the stop member. By virtue of this structural feature it seems apparent that external wear of the member 5 can in no way affect relative alignment of the top 1 and the box member.

At its forward ends the skirt 11 flares slightly and terminates in ears 15 which have neither surfaces 16 overlying the annular upper surface of the box member 5. These surfaces therefore serve to act as fulcrums, when the stop member 1 is tilted forward whereby the lip 13 may be lifted from within the box member 5 when using the device in the intended manner as will be more fully described.

Lugs 27 extend downwardly from the ears 15 and are engageable with the periphery of the box member 5 and hence assist in guiding the stop member into position upon the box member and also prevent its sideward movement thereon when the guide is being removed from stabbing position. These lugs may be of generally rectangular cross section, as shown in Figs. 1, 2 and 3, or they may be tapered downwardly and inwardly, as shown at 18 in Fig. 4.

Secured to the exterior of the stop member 1 is an arm 29 having inclined upper portion 21 and horizontal lower portion 22 inter-connected by the vertical portion 23. This arm terminates at its lower end in the yoke 24, which is preferably arcuate to fit upon and rest against the pipe section 6, whereby the upright position of the stop member 1 upon the box member 5 is determined. At the same time this arm and yoke assembly assists in holding the stop member 1 rigidly in position against the force exerted by the member 3 swinging into engagement therewith. The loop formed by the configuration of the arm 29 provides space for the spinning rope 25 and the tongs 26, both shown in dotted outline, so that each of these devices may be maintained in position for immediate use when the stabbing operation is complete.

To facilitate handling of the device as thus far described the handle 27 is secured to and extends rearwardly of the arm 29.

In the operation of the device it is assumed that the tongs 26 and the spinning line 25 are in position for use in make-up operations as soon as a section of drill string or pipe 4 is swung into position above the section 6 already in the well. To effect desired alignment of the section 4 with the section 6 the device above described is manually positioned upon the box member 5 and the handle 27 is lowered until the yoke 24 engages the pipe section 6 at a point spaced below the upper end of the box member.

As the handle 27 is lowered the lip 13 moves into the counterbore of the box 5 for engagement with the inner periphery thereof adjacent its end.

As the pipe 4 and the pin member 3 thereon are swung toward position of alignment with the box 5 and the pipe section 6 they may readily be guided in their movement to engage the stop 1 which will arrest such movement when the section is directly above the box member. The pin will be guided into the box 5 as the pipe section 4 is lowered. When this is accomplished the handle 27 is lifted, whereby the lip 13 rises from within the counterbore of the box 5 while the surfaces 16 act as fulcrums upon the top of the box. The entire device is then manually withdrawn radially from stabbing position so that the spinning line or rope 20 can be slipped upwardly onto the pin member 3 or the pipe section 4 as the case may be. A pull upon the spinning line 25 will make up the joint whereupon an additional tong may be applied above the tong 26 for the final bucking-up operation.

The invention claimed is:

1. A stabbing device for drill and pipe strings where a lower box section is held stationary in a vertical position and a pin section is to be swung into alignment thereabove including, an arcuate stop member having a body portion open at one side adapted to be positioned upon the box section, said body portion having a tapered inner surface to stop and guide said pin section into the box section, an arcuate lip formed on and extending downwardly from the stop member and adapted to enter and engage the inner periphery of the section to resist the force exerted in stopping the movement of the pin section into aligned position thereabove, and handle means mounted on the body portion of the stop member.

2. A stabbing device for drill and pipe strings where a lower box section is held stationary in a vertical position and a pin section is to be swung into alignment thereabove including, an arcuate stop member having a body portion open at one side adapted to be positioned upon the box section, said body portion having a tapered inner surface to stop and guide said pin section into the box section, a pair of spaced downwardly extending lugs on said member proximate the forward edges of the member to engage the stationary section and restrain the member from movement transversely of said box section, an arcuate lip extending downwardly from the stop member intermediate said lugs to enter and engage the inner periphery of the box section to resist the force exerted upon the stop member in stopping the movement of the pin section into aligned position thereabove, and handle means mounted on the body member.

3. In a pipe stabbing device, an arcuate stop member having a body portion open at one side and having a downwardly extending arcuate lip thereon tapering toward its ends, ears on the member proximate the ends of said lip formed on and extending forwardly from said lip to fulcrum upon a pipe section upon which the member is positioned whereby said lip is lifted by tilting of the member, and handle means mounted on the body portion of the stop member.

4. A pipe stabbing device comprising an arcuate stop member having a body portion open at one side and having a tapered arcuate inner surface, adapted to be engaged by a member to be

guided thereby, means comprising at least two downwardly extending spaced lugs on the member for peripherally engaging the end of a pipe and restraining the member from radial movement upon the end of the pipe, and an arm secured to said member and extending downwardly and engageable with the pipe to stabilize the member in position thereon, said arm extending outwardly intermediate its end to form a closed loop.
